UNITED STATES PATENT OFFICE.

GEORGE J. DOURTE, OF DENVER, COLORADO.

VALVELESS PUMP.

1,312,962.

Specification of Letters Patent. Patented Aug. 12, 1919.

Application filed July 26, 1916. Serial No. 111,349.

To all whom it may concern:

Be it known that I, GEORGE J. DOURTE, a citizen of the United States, residing at Denver, in the county of Denver and State of Colorado, have invented certain new and useful Improvements in Valveless Pumps, of which the following is a specification.

This invention relates to valveless-pumps of the type shown in my United States Patent No. 1,034,592, issued August 6, 1912, in which a piston has a combined rotary and reciprocal movement in a cylinder provided with openings for the admission and discharge of liquid.

The primary object of the present invention resides in providing certain modifications in the design and arrangement of the coöperative parts of the pump, to simplify its construction and increase its efficiency in operation.

Principal among these improvements is a piston composed of relatively connected parts which by frictional engagement with the cylinder-wall, insure a water-tight contact at the points of ingress and egress of the displaced liquid and thus obviate the use of packing devices such as are employed in the construction disclosed in the above-mentioned patent.

Another improvement resides in the provision of means for equalizing the water pressure upon the circumferential surface of the rotary and reciprocating piston and thereby minimize the friction to which it is subjected in the operation of the pump.

With the above and other objects in view, all of which will fully appear in the course of the following description, my invention consists of the novel features of construction and arrangement of parts illustrated in the accompanying drawings in the various views of which like parts are similarly designated and in which—

Figure 1 represents an elevation of my improved pump in duplex form,

Fig. 2, a vertical section taken along the line 2—2, Fig. 1,

Fig. 3, an enlarged section along the line 3—3, Fig. 2,

Fig. 4, an enlarged section along the line 4—4, Fig. 2,

Figs. 5, 6 and 7, sectional elevations of

one of the pump-cylinders and pistons showing the positions the latter assumes at different points in the cycle of operations of the pump,

Fig. 8, a longitudinal section of one of the pistons,

Fig. 9, a transverse section taken along the line 9—9, Fig. 8,

Fig. 10, a transverse section along the line 10—10, Fig. 8,

Fig. 11, an elevation of a piston used in a pump of the double-acting balanced type,

Fig. 12, a vertical section similar to that of Fig. 2, showing the construction and co-operative arrangement of the parts of a pump of the double-acting balanced type,

Fig. 13, a section taken along the line 13—13, Fig. 12,

Fig. 14, a transverse section through the cylinder and piston shown in Fig. 12 taken along the line 14—14,

Fig. 15, a section similar to that shown in Fig. 14, showing the position of the piston at the ends of its strokes,

Fig. 16, a section similar to that shown in Fig. 14, showing the construction and arrangement of the parts in a pump of the single-acting balanced type, and

Fig. 17, a section similar to that of Fig. 16 showing the position of the piston in a pump of the last-mentioned type at the end of its up or downward stroke.

Referring first to the construction shown in Figs. 1 to 10 of the drawings, my improved pump consists of one or more cylinders 2 mounted in a vertical position upon a base 3.

Each cylinder has at its upper end a stuffing-box 4 affording a fluid-tight passage for a piston-rod 5, and in its wall at points intermediate of its ends, diametrically opposite ports 7 and 6 for the ingress and egress of the liquid displaced in the operation of the pump.

The ingress-port 7 of the cylinder connects with a conduit 8 which extends into the source of liquid supply, and the egress port 6 connects with a discharge-conduit 9 which as usual is in communication with an air-chamber 10.

A piston 12 connected with the rod 5 extending through the stuffing-box 4 is longi-

tudinally divided into two complementary halves one of which is rigidly secured at the end of the rod.

The plane along which the piston is divided, is offset, as at 13, to obstruct the flow of liquid between the spaces of the cylinder at opposite sides of the piston, and coiled springs 14 disposed in recesses in the face of one of the halves at which it engages the other half, are provided to force the two parts into frictional engagement with the interior surface of the cylinder in which the piston has its movement.

The springs are preferably arranged in pairs at opposite ends of the piston, and in order to adjust their tension they are placed in engagement with the ends of bolts 15 disposed at the lower end of the piston, in threaded portions of the before-mentioned recesses, and at the opposite end of the same, in threaded openings in the half opposite that which contains the springs.

The piston has, interiorly, two separated channels 16 which serve to connect diametrically opposite, longitudinally extending slot-like openings 17 in the circumferential surface of the piston, respectively with openings 18 in the end faces of the same.

The cylinder is preferably lined with a bushing 19 to reduce friction and facilitate adjustment in case of wear.

The piston-and-cylinder construction as described is designed for use in a double-acting pump which delivers water at each single stroke of the piston, and in this respect varies from the construction shown and described in my above-mentioned patent, which is of the single-acting type and discharges water only at each alternate stroke of the piston.

In the operation of my improved pump, a combined reciprocal and rotary movement is imparted to the piston through the intermediary of a driving mechanism which in principle is similar to that disclosed in United States Patent No. 1,010,604 issued to me on December 5, 1911.

A crank-shaft 38 rotatably mounted in boxes 20 of a standard 42 erected on the base 50 of the pump, is by means of a gear wheel 21 and a pinion 22, operatively connected with a counter-shaft 23 which carries a pulley 24 for its connection with a motor or other source of mechanical energy and which is supported in a box 43 on the same standard.

The piston-rod 5 is at its upper end attached to a cylindrical cross head 25 which has combined reciprocal and rotary movements in a guiding sleeve 26 which is formed integrally with the standard or otherwise secured thereto.

The sleeve is lined with a bushing 27 for the usual purpose and the cross-head has an

axial recess open at its upper end to receive the complementary halves of a socket-bearing 28 which is part of a universal joint for connecting the cross-head with a connecting rod 29.

The rod 29 has at its lower end a ball 30 which occupies the socket of the bearing and it extends through an opening in the upper end of the same which permits of an oscillatory motion of the rod in following the movement of the crank on the shaft 75 with which its upper end connects.

To compel the cross-head to rotate with the connecting rod and thereby impart a rotary movement to the piston, the ball at the end of the connecting-rod is provided with a slot, and a pin 31 extending loosely through said slot is secured in alined openings in the cross-head as is best shown in Figs. 3 and 4.

A hollow nut 32 screwed into the threaded upper end of the recess of the cross-head, serves to hold the halves of the socket bearing in their relative positions and may be used to take up wear.

The connecting rod extends at its upper end loosely through a sleeve 33 at the lower end of a yoke 34 which has a head 35 for connection with the wrist 36 on a crank wheel 37 at an end of the before-mentioned crank-shaft 38.

A beveled gear-wheel 39 fixed at the end of the connecting rod between the arms of the yoke, meshes with a similar wheel 40 which is fixed on the before-mentioned wrist of the crank-shaft, and a collar 41 on the rod 100 at the opposite end of the sleeve 33, coöperates with the gear-wheel 39 to hold the rod and the yoke against relative displacement.

In the operation of the pump, the piston is by movement of the crank-shaft moved 105 up and downwardly in the cylinder and is at the same time rotated about its longitudinal axis by the coöperative engagement of the beveled gear-wheels, and the ball and socket connection and the cross head.

The beveled gear-wheels are in the present construction, of equal size so that the piston during each stroke will make one-half a revolution about its axis and complete a revolution during each reciprocating motion.

At the beginning of either its up or downward stroke, the piston is in the positions shown in Figs. 5 and 7 of the drawings, in which its slots are positioned at an angle of 90° with relation to the ports of the cylinder and in consequence are out of alinement therewith, it being observed that the ports and the slots are of substantially equal width.

When by rotation of the crank shaft the piston is moved up or downwardly, it is at the same time compelled to rotate about its

axis by the coöperative engagement of the gears 39 and 40, with the result that while it advances in the cylinder its slotted openings 17 are gradually moved into register 5 with the respective ports of the same.

When the piston has reached the center of its stroke as shown in Fig. 6, its slots are in complete register with the ports, and as the piston continues its movement, they are 10 gradually separated from the same until at the end of the stroke the ports and slots are again placed out of alinement, and at an angle of 90° with relation to each other.

The liquid drawn into the cylinder 15 through its suction port 7 by the movement of the piston, flows through the respective passage 16 and the corresponding opening 18 in the end of the piston, into the space of the cylinder rearward of the piston with relation to the direction of its travel, while the 20 liquid contained in the space of the cylinder at the opposite side of the piston, is at the same time forced through the passage in the opposite half of the piston to and through 25 the port 6 and into the discharge conduit 9.

It will thus be seen that during each stroke of the piston, a quantity of liquid is discharged through the egress port of the cylinder, while a similar quantity is drawn 30 in through the ingress port of the same, and the quantities of water thus intermittently displaced in rapid succession will produce a substantially continuous flow of liquid at the delivery end of the discharge conduit.

35 In the construction shown in Figs. 1 and 2 of the drawings, two cylinders are mounted on the pump base at opposite sides of the standard, and the pistons in the cylinders are by the mechanism hereinbefore described, connected with separated crank 40 wheels on the shaft 38, the wrists of which are placed at an angle of 90° with relation to each other.

The ingress and egress ports of the cylinder of the duplex pump thus formed are as usual connected by one intake conduit and one discharge conduit and it will be understood without further illustration that three or more cylinders and pistons may in like 50 manner be coöperatively combined to form multiplex pumps of any desired number of units.

In order to reduce the friction between the piston and the cylinder in which it has 55 its movement and thus increase the efficiency of the machine, I provide the balanced type of pump illustrated in Figs. 11 to 17.

In this pump the pressure upon the piston is equalized by providing the cylinder with 60 two ingress ports and two egress ports placed respectively opposite to each other, each two ports being connected with a common conduit for the conveyance of liquid to and from the same as shown in Figs. 14 and 16.

In a pump of this character, it is obviously necessary that the slotted openings in the circumferential surface of the piston are at the end of the strokes in a position intermediate of the ports in the cylinder wall, which are disposed at quadrant points 70 thereof.

It follows that the piston must during each stroke rotate through an arc of 90° in order to bring its slots in complete register with the ports or cylinder at the center of 75 the movement and again out of alinement with the same when its movement is completed, and that in consequence the piston makes but one-half a revolution during each reciprocation.

To accomplish this result the gears on the shaft and the connecting rods are proportioned as 2 to 1 as is shown in Fig. 12 of the drawings.

In a single acting pump of the balanced-type (Figs. 16 and 17) the construction of the piston is the same as that of the unbalanced double-acting type shown in Figs. 1 to 10, but to equalize the pressure upon the piston in a double-acting pump, by doubling the ingress and egress ports of its cylinder, it is necessary that the piston have four openings and corresponding passages to correspond with the ports in the cylinder in which it has its movement.

A construction of this kind has been illustrated in Figs. 12 to 15 in which the piston has four separated passages connecting with slots disposed at quadrant points of its peripheral surface.

Two opposite passages connect with openings at one end of the piston and the two other passages connect with openings at the opposite end of the same.

The operation of pumps of the balanced type is the same as that of the first-described pump of the unbalanced type with the exception that in duplex pumps of the balanced type, the cranks on the cross head are placed at an angle of 180° with relation to each other.

Having thus described my invention in the best forms at present known to me I desire it understood that many variations in the construction and arrangement of its parts may be made without departing from the spirit of the invention or sacrificing any of the advantages of the same.

It may, for example, be found necessary under certain conditions to change the continuous rotary movement of the piston to a reciprocating rotary motion, by automatically reversing its direction of rotation at predetermined points in the revolution of the crank-shaft.

It may also be found advantageous to rotate the piston intermittently at the ends of its strokes and thereby preserve its com-

plete registration with the cylinder ports during the greater extent of its reciprocating motion.

Movements for accomplishing these objects have been fully shown and described in my Patent No. 1,010,604 hereinbefore referred to, and the modifications have for that reason not been illustrated in the present application.

10 Having thus described my invention what I claim and desire to secure by Letters-Patent is:

1. In combination, a cylinder having oppositely disposed ingress-ports and an egress-port, a piston to reciprocate in said cylinder, having openings adapted to register simultaneously with said ingress ports and to register with said egress-port, and passages connecting said openings with the interior of the cylinder, mechanism to reciprocate the piston, and means to simultaneously rotate the same, whereby to bring the openings of the piston in register with the ports of the cylinder during determinate periods in its reciprocal motion.

2. In combination, a cylinder having oppositely disposed ingress-ports and oppositely disposed egress-ports, a piston to reciprocate in said cylinder, having openings adapted to register with said ingress ports and with said egress ports, and passages connecting said openings with the interior of the cylinder, mechanism to reciprocate the piston, and means to simultaneously rotate the same, whereby to bring the openings of the piston in register with the ports of the cylinder during determinate periods in its reciprocal motion.

3. In combination, a cylinder having oppositely disposed ingress ports and an egress-port, a piston to reciprocate in the cylinder, having two pairs of oppositely disposed openings to register simultaneously with said ports, and passages connecting said openings with the spaces of the cylinder at opposite sides of the piston, mechanism for reciprocating the piston, and means to simultaneously rotate the same whereby to bring the openings of the piston in register with the ports of the cylinder during determinate periods in its reciprocating movement.

4. In combination, a cylinder having oppositely disposed ingress-ports, and oppositely disposed egress-ports, a piston to reciprocate in the cylinder, having two pairs of oppositely disposed openings to register simultaneously with said ports, and passages connecting said openings with the spaces of the cylinder at opposite sides of the piston, mechanism for reciprocating the piston, and means to simultaneously rotate

the same whereby to bring the openings of the piston in register with the ports of the cylinder during determinate periods in its reciprocating movement.

5. In combination, a ported cylinder, and a piston to reciprocate in said cylinder, adapted to cover and uncover the ports of the same and composed of parts one of which is recessed, springs in the recesses for continuously forcing said parts into fluid-tight engagement with the cylinder, and screws providing abutments for said springs and capable of adjustment to vary the tension of the same.

6. In a pump of the character described, the combination with a ported cylinder, of a cylindrical piston fitted therein for reciprocation and provided with ports to register with the ports of the cylinder, said piston being longitudinally divided into two halves each having a port in its circumference, an opening in one of its ends, and a passage connecting said port and said opening, a piston-rod attached to one of said halves, and springs between said halves to continuously force them into fluid-tight engagement with the cylinder.

7. In a pump of the character described, the combination with a ported cylinder, of a cylindrical piston fitted therein for reciprocation and provided with ports to register with the ports of the cylinder, said piston being longitudinally divided into two halves each having a port in its circumference, an opening in one of its ends, and a passage connecting said port and said opening, a piston-rod attached to one of said halves, and springs between said halves to continuously force them into fluid-tight engagement with the cylinder, there being recesses in said piston-halves for the reception of said springs.

8. In a pump of the character described, the combination with a ported cylinder of a cylindrical piston fitted therein for reciprocation and provided with ports to register with the ports of the cylinder, said piston being longitudinally divided into two halves each having a port in its circumference, an opening in one of its ends, and a passage connecting said port and said opening, a piston-rod attached to one of said halves, springs between said halves to continuously force them into fluid-tight engagement with the cylinder, and screws for the adjustment of said springs.

In testimony whereof I have affixed my signature in presence of two witnesses.

GEORGE J. DOURTE.
